UNITED STATES PATENT OFFICE.

CHARLES SPARKS, OF ST. LOUIS, MISSOURI.

SCORE-BOOK FOR THE GAME OF GOLF.

SPECIFICATION forming part of Letters Patent No. 690,123, dated December 31, 1901.

Application filed March 30, 1901. Serial No. 53,582. (No model.)

To all whom it may concern:

Be it known that I, CHARLES SPARKS, a citizen of the United States, residing in the city of St. Louis, in the State of Missouri, have invented certain new and useful Improvements in Score-Books for the Game of Golf, of which the following is a full, clear, and exact description, reference being had to the accompanying drawings, forming part of this specification.

My invention relates to a book for use in keeping a score or tally in playing the game of golf, the object of the invention being to produce a series of sectional tally-sheets for recording the number of strokes required by the players in depositing the ball in the successive holes over the course on which the game is played.

My invention consists in features of novelty hereinafter fully described, and pointed out in the claim.

Figure I is a perspective view of the score-book. Fig. II is a detail view of one of the sheets of the book.

1 designates the cover of the book, provided with spaces for the names of the players and such other memoranda as it may be desired to place thereon.

2 designates the sheets, of which there are preferably two series, one for the outgoing trip on the course and the other for the incoming trip on the course. The sheets 2 bear consecutive numerals, "1," "2," "3," &c., that indicate the holes of the course over which the game is played, there being one sheet for each hole contained by the course. Each sheet 2 is divided up into two series of sections, one of said series of sections being indicated by 3 and the other series by 4. The sections 3 and 4 are numbered from "1" up to any desirable number, such as "14," as shown in the drawings, and they are adapted to be separated from each other on scored lines A, B, and C. One of the series of sections 3 or 4 is designed to contain indication of one of the players and the other section contains indication of the other player, the indications being such as the words "Self" and "Opponent," and thereby the scores or

tallies of the players may be individually shown side by side.

The use of the score-book is as follows: When a player has, for instance, begun a game and succeeded in getting the golf-ball into the first hole of the course by a series of 55 strokes, the sections 3 or 4 of his series on the book are torn from the sheet 2 corresponding to the number of the hole into which his ball has been deposited sufficiently to leave only the sections 3 or 4, bearing numerals corresponding to the number of strokes required by the player in putting the ball into the hole. When the other player has put the ball into the hole, a portion of the series of sections is detached to leave only sections of the series 65 on his side of the score-sheet corresponding to the number of strokes required by him in depositing the ball in the hole. To illustrate, reference may be had to Fig. I of the drawing and the first sheet thereof relating to the 70 first hole. I have there shown that the party keeping the score and indicated as "Self" succeeds in depositing the ball in the first hole with three strokes. All of the sections 3 are torn off except those numbered "1," 75 "2," and "3," thereby indicating the number of strokes required in reaching the first hole with the ball. The "Opponent" having deposited the ball in the first hole in four strokes, a portion of the sections 4 is torn off, leaving 80 only the sections numbered up to "4," thereby indicating that the hole was reached with four strokes. The same applies to the second sheet. "Self" is there indicated as having reached the second hole by striking the 85 ball seven times and "Opponent" by striking it five times. It will be readily understood that the score of the strokes required in reaching the remainder of the holes is kept in the same manner as that described both in 90 the outgoing trip on the course and on the incoming trip.

I claim as my invention—

A golf score-book comprising a series of consecutively-numbered sheets, one for each hole in the course, in and out, a series of perforated lines dividing each sheet into two series of sections, each series being numbered

consecutively beginning with the number 1, each section being separated from the others by said lines of perforations, one series of sections containing indications designating one player while the other series of sections contain indications designating another player whereby the scores or tallies

of the players may be individually shown on one sheet for the respective holes in the course.

CHAS. SPARKS.

In presence of—

E. S. KNIGHT,
N. V. ALEXANDER.
